BARREL LIFTER

Roy S. Trimble, 1021 Capitol, Beacon Hill Station,
San Antonio, Tex. 78201
Filed Oct. 14, 1965, Ser. No. 495,916
8 Claims. (Cl. 254—131)

This invention relates to a barrel lifter, and has as its primary object the provision of a tool for lifting a barrel, particularly a flanged barrel such as an oil drum or the like from a horizontal to a vertical position with a minimum of time, effort and difficulty.

An additional object of the invention resides in the provision of means in association with such a barrel lifter for removing or replacing the usual large and small threaded plugs which comprise a component of such barrels or drums.

A further object of the invention is the provision of a device of this nature which will facilitate the general handling, opening and reclosing or venting of such drums.

Still another object of the invention is the provision of a tool of this nature which is sturdy and durable in construction, reliable and efficient in operation, and simple and inexpensive to manufacture.

Still other objects reside in the combinations of elements, arrangements of parts, and features of construction, all as will be more fully described hereinafter and disclosed in the accompanying drawing wherein there is shown a preferred embodiment of this inventive concept.

In the drawing:

FIGURE 1 is a top plan view of one form of device embodying the instant inventive concept;

FIGURE 2 is a side elevational view thereof;

FIGURE 3 is a bottom plan view of the device;

FIGURE 4 is an end elevational view of the device as viewed from the left in FIGURE 1;

FIGURE 5 is a side elevational view showing the device in position to lift a barrel from a horizontal position to a vertical position, a period of adjustment during the lifting operation being indicated in dotted lines;

FIGURE 6 is a fragmentary side elevational view showing a portion of the tool employed in the removal of a small threaded plug from the top drum or barrel;

FIGURE 7 is a fragmentary view on a reduced scale showing the device employed can manipulate the large plug in the side of a drum or the like; and

FIGURE 8 is a view similar to FIGURE 7 showing the employment of the device for removing the large plug in the top of the drum.

Similar reference characters refer to similar parts throughout the several views of the drawing.

Having reference now to the drawings in detail, the barrel lifter of the instant invention is generally indicated at 10, and comprises a generally U-shaped member which may be formed of a suitable metal, such as steel, and which may be of tubular construction, if desired for the purpose of lightness, which includes a pair of aligned legs 11 connected by a bight 12. As best shown in FIGURE 2 at an intermediate point the legs are bent at an angle of approximately 15° as indicated at 13. At their outer ends the legs 11 are connected by a transverse tubular piece 14 of arcuate configuration, conforming an arc generally to the radius of curvature of a conventional 55 gallon steel drum. The ends of the legs 11 are flattened as at 15, and secured in any desired manner as by spot welding 16 to arcuate member 14. A rectangular protrusion 17, the purpose of which will be more fully described hereinafter, extends outwardly from the approximate center of arcuate member 14.

Extending from a point on the inner side of the angularly inclined portion of each leg 11 is a rectangular bar 18,

2

which extends past the angle 13, in relative parallelism to the portion of the bar on the opposite side of the angle. Each member 18 is suitably spot welded as at 19 or otherwise connected to the underside of each leg 11, and at a point adjacent its outer extremity is connected to a support 20, as by spot welding 21, the support 20 in turn being connected to the adjacent leg 11 by spot welding or the like as indicated at 21. As a result a protuberance or projection 22 extends beyond each support in substantial parallelism to the adjacent portion of the angled leg 11.

5 A generally U-shaped member 25, including a pair of upstanding lugs 26 and the bight 27 is secured as by spot welding 28 to the side of one of legs 11 opposite the obtuse angle 13, or on the side opposite the bar 18, and serves as a lug wrench, in a manner to be more fully described hereinafter.

10 While the device may be employed as a lifter for many types and varieties of drums, it is particularly applicable to a conventional 55 gallon oil drum of metal construction, such drum being generally indicated at 30 and partially broken away as indicated. The drum 30 is provided at each end with an annular flange 31, about its head 32, the head 32 being provided normally with a relatively small screw-threaded plug 33 and a relatively large threaded plug 34. A similar plug 35 is provided usually in the side of the barrel, to facilitate filling or removal of the contents.

15 In the use and operation of the device, particularly when it is desired to lift a barrel from a horizontal to a vertical position as shown in FIGURE 5, the member 10 is positioned as shown, with one portion of the angled legs 11 extending along the arcuate side of the barrel and the member 14 seating firmly against the side wall thereof, and being pointed out that the radius of curvature of arcuate member 14 is such as to conform smoothly and evenly to the side of the barrel, preferably immediately adjacent one of the ribs or corrugations 36 which form, conventionally, a portion of such drums. The protruding ends 22 of bars 18 then engage beneath flange 31, with the supports 20 serving as limit stops, and further to prevent slippage of the device, and the lifting force is exerted on the bight 12, in the direction indicated by the arrow in FIGURE 5. The leverage thus afforded permits the barrel to be raised to an upright position with a minimum of effort and difficulty.

20 The protruding lug or protuberance 17 is dimensioned to serve as a cap wrench for the small plug 33, and when it is desired to remove or replace such plug, the protuberance or lug 17 is simply inserted in the end of the small plug, as shown in FIGURE 6, and the plug rotated until removed or tightened as desired.

25 FIGURE 7 shows the device employed as a cap wrench for removing the side plug 35 from the barrel. In this case, the cap wrench 25 is positioned so as to engage the sides of the large threaded plug 35, then the device rotated until the plug is removed or tightened. A similar usage is shown in FIGURE 8 wherein the large cap wrench 25 is applied to the large plug 34 in the top of the drum.

30 Obviously, the device may be made with any suitable material of sufficient strength, and equally obviously of any desired size for the purpose intended, although an overall length of approximately three feet has been found desirable for use with the particular drum specified.

35 From the foregoing it will now be seen that there is herein provided a device which accomplishes all of the objects of this invention, and others, including many advantages of great practical utility and commercial importance.

40 As many embodiments may be made of this inventive

concept, and as many modifications may be made of the embodiment hereinbefore shown and described, it is to be understood that all matter herein is to be interpreted merely as illustrative and not in a limiting sense.

I claim:

1. In a barrel lifter, a body portion comprising a pair of aligned legs and a bight connecting said legs at one end, said legs being obtusely angled at an intermediate point in a direction transverse to the extension of said bight, a bar secured to each leg on one side of the angle therein and extending across said angle in substantially parallelism to the portion of the leg on the other side of the angle, a support extending from each leg on said other side of the angle rigidly connected to the adjacent bar, a portion of each bar extending beyond its support and adapted to engage beneath the flange of flanged barrel to be lifted, and an arcuate end member secured across the ends of said legs opposite said bight adapted to bear against the arcuate side of the barrel to be lifted, whereby lifting pressure exerted on said bight is adapted to raise the barrel from a horizontal position to a vertical position.

2. The structure of claim 1 wherein said barrel lifter is provided with a small cap wrench adapted to engage a conventional small plug of a steel drum for removal and replacement.

3. The structure of claim 2 wherein said small cap wrench comprises an elongated generally rectangular lug extending outwardly relative to said legs from the approximate center of said end member and adapted to engage in the recess conventionally provided in the small threaded plug.

4. The structure of claim 1 wherein said barrel lifter

is provided with a large cap wrench adapted to engage a conventional large plug of a steel drum for removal and replacement.

5. The structure of claim 4 wherein said large cap wrench comprises a generally U-shaped member adapted to engage the opposite exterior sides of the conventional large plug positioned on one of said legs at an intermediate point on the side opposite from its associated bar.

6. The structure of claim 2 wherein said barrel lifter is also provided with a large cap wrench adapted to engage a conventional large plug of a steel drum for removal and replacement.

7. The structure of claim 6 wherein said small cap wrench comprises an elongated generally rectangular lug extending outwardly relative to said legs from the approximate center of said end member and adapted to engage in the recess conventionally provided in the small threaded plug.

8. The structure of claim 7 wherein said large cap wrench comprises a generally U-shaped member adapted to engage the opposite exterior sides of the conventional large plug positioned on one of said legs at an intermediate point on the side opposite from its associated bar.
